United States Patent Office

Des. 194,842
Patented Mar. 19, 1963

194,842

TIE CLASP

John Berzac, 20536 Cedar, St. Clair Shores, Mich.

Filed Oct. 4, 1962, Ser. No. 71,987

Term of patent 14 years

(Cl. D17—10)

FIG. 1.

FIG. 2.

FIG. 3.

FIG. 1 is a front elevational view of a tie clasp illustrating my new design;

FIG. 2 is a rear elevational view thereof; and

FIG. 3 is a bottom view thereof.

I claim:

The ornamental design for a tie clasp, substantially as shown.
